US00D834879S

(12) **United States Design Patent** (10) **Patent No.:** **US D834,879 S**
(45) **Date of Patent:** **** Dec. 4, 2018**

(54) **CONTAINER LID**

(71) Applicant: **VITA-MIX MANAGEMENT CORPORATION**, Olmsted Township, OH (US)

(72) Inventors: **Brenton Krivos**, Brunswick, OH (US); **Jack Warren Gee**, Willoughby, OH (US); **Phonesacksth Guy Kettavong**, Medina, OH (US)

(73) Assignee: **VITA-MIX MANAGEMENT CORPORATION**, Olmsted Township, OH (US)

(**) Term: **15 Years**

(21) Appl. No.: **29/557,017**

(22) Filed: **Mar. 4, 2016**

(51) LOC (11) Cl. **07-01**

(52) U.S. Cl. **D7/391**
USPC **D7/391**

(58) **Field of Classification Search**

USPC D3/272, 273, 274-276, 279, 282, 232, D3/302, 200, 201, 202, 203.1, 203.2, 270, D3/271.1, 304, 306, 309-315, 318, 319, D3/901, 903, 904; D7/300, 306, 325, D7/376, 381, 387, 392, 360, 392.1, 391, D7/393, 396.1, 396.2, 396.3, 396.4, 507, D7/509-511, 542, 546, 555, 558, 605, D7/608, 629, 665, 736, 738, 900, 321, D7/323, 354, 359, 412, 417, 500, 505, D7/509-511, 513, 533, 538-545, 549, D7/550.1, 552.1, 552.2, 553.1, 553.2, D7/553.4, 553.5, 553.6, 553.7, 554.1, D7/566, 568, 584, 586, 600.1, 601, 602, D7/607, 609, 610, 614, 615, 698, 703; D9/421, 429, 434-447, 449, 504, 780, D9/414, 424-432, 435, 438, 451-452, D9/415, 416, 418, 419, 420, 423, 425, D9/428-454, 457, 499, 500, 502-503,

D9/516, 517, 529, 549, 552.1, 557, 558, D9/561, 571, 630, 682, 686, 688, 690, D9/692, 703, 737, 738, 740, 741, 744, (Continued)

CLAIM

The ornamental design for a container lid, as shown and described.

DESCRIPTION

FIG. 1 is a perspective view of a container lid showing our new design;

FIG. 2 is a first side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

The broken lines are shown for the purpose of illustrating parts of the article that form no part of the claim.

1 Claim, 4 Drawing Sheets
